FUSIBLE CONTROL FOR MANUALLY
ADJUSTABLE DEVICES

Samuel W. Rushmore, Plainfield, N. J.

Application April 11, 1938, Serial No. 201,325
Renewed June 20, 1939

16 Claims. (Cl. 123—108)

My present invention is shown as embodied in means for limiting or modifying the opening movement of throttles for internal combustion engines; particularly for those of the motor-vehicle type; and, more specifically, to means for interposing substantial or complete resistance to opening the throttle beyond a predetermined limit, thereby to prevent racing the engine until it is warmed and lubricated sufficiently to prevent undue wear on pistons and cylinders. But it will be obvious that certain features of my invention are applicable to limiting or preventing movement of other manually adjustable control devices, where it is desired to have their range of adjustment dependent on the temperature of the device controlled thereby.

For such purposes, I employ as a temperature-sensitive, resistance-varying element, a body of fusible material contained in a receptacle which is in heat receiving relation to a portion of the engine in which temperature variations during the warming-up period, correspond roughly with the cylinder wall and lubricant temperatures.

This fusible material has a melting point such that it is normally a solid operating to obstruct and limit the movement of the throttle during the warming-up period, but when sufficiently heated by warming up of the engine, it will melt and permit maximum movement of the controller.

The fusible material may operate either directly or through a stop element having one portion submerged in said fusible material, and another portion extending into operative relation for obstructing a movable element of the throttle controls.

For the specific purpose of controlling the throttle of an automobile engine, I prefer to arrange the fusible material in close heat transfer relation with the cooling water in the head jacket of the engine. The fusible material may be cadmium-tin-lead-bismuth alloy, these alloys being available in proportions affording solidification points anywhere between, say, 133° F. and 203° F. Alloys including this range are specified in Smithsonian physical tables. (See, for instance, 2nd reprint of 7th revised edition, published 1923 by the Smithsonian Institution.) Obviously, however, there are other fusible materials, produced since 1923, which are now on the market, and may be even more useful for my purposes.

The fusible material of the desired melting point may be located in a pocket in or secured to the outer wall of the head jacket.

When used as an attachment, it may be simply a container or tank brazed or otherwise secured in intimate contact with the exterior vertical wall of the head jacket. Because of its high heat conductivity, copper is a suitable metal for such container or tank.

The throttle obstructing device may be a plunger which, when the fusible material is melted, is non-positively urged upward to its operative relation with the throttle control elements. This may be accomplished by having the submerged portion of the plunger made of a material which is of much less specific gravity than the fusible material. In the case of the alloys above referred to, a solid or hollow aluminum float may serve the purpose, such alloys in liquid state being approximately 3½ times the weight of an equal volume of solid aluminum, and the ratio is not much less for certain solid aluminum alloys or mixtures that may be employed. A spring may be employed to urge the plunger upward. Where the plunger is a float, the spring will supplement flotation; and where the spring is submerged in the fusible material, the plunger need not be a float.

The above and other features of my invention may be more readily understood from the following description in connection with the accompanying drawings, in which

Fig. 1 is a side elevation, partly in vertical section, showing my invention as applied to the throttle of a downflow intake for an internal combustion engine;

Fig. 2 is a detail section on the line 2—2 of Fig. 1; showing a form wherein the fusible metal cavity and the float are cylindrical;

Fig. 3 is a similar section on line 2—2, Fig. 1, but showing the float and cavity as oblong instead of circular;

Fig. 4 is a view like Fig. 1, but showing a modification;

Fig. 5 is a detail section on line 5—5, Fig. 4;

Fig. 6 is a vertical section of a fusible metal container located as in Fig. 4, but having the stop for the throttle, in the form of a laterally flexible spring that has fixed anchorage in the bottom of the container for fusible metal; and

Fig. 7 is a view like Fig. 1, but showing a third modification.

In Fig. 1, the downflow intake 1 is throttled by butterfly valve 2, controlled by lever 3.

The variable resistance stop for limiting initial opening of the throttle includes the receptacle 4 containing the fusible metal 5, in which is submerged the float 6, supporting the verti-

cally slidable stop element 7. The receptacle 4 is in intimate heat transfer relation with the water cooled head jacket 10, of the engine. A stiff spring 8 projects radially from and rotates with the throttle control. In this particular form of the device, the spring 8 is backed by a rigid lever 9. When the throttle valve 2 is rotated to open it, the backing lever 9 and spring 8, swing downward, as a unit through a short arc, a; whereupon the part of the spring 8 which projects beyond the backing lever 9, engages the stop 7. When the engine is cold the float is solidly frozen in the fusible metal 5, thereby preventing further downward movement of the stop, but the throttle may be freely adjusted throughout the relatively short arc a. After the engine has been warmed up enough to melt the fusible metal 5, the stop may be forced downward by the spring 8 through the further arc b, in which extreme lower position the throttle valve 2 is wide open, and the float 6 is deeply submerged.

Thus the backing lever 9 and the free end of the spring 8 are in effect a unitary cam element designed to be positively stopped by stop 7, until the motor is warmed up, and to force the stop 7 downward as soon as the fusible metal 5 is heated enough to melt.

The tip of the spring 8 will be more yieldable if the spring is not secured to the backing lever 9 except at the end nearest the throttle.

As shown in Fig. 2, receptacle 4 has a broad base of engagement with the head jacket 10, so as to readily absorb heat therefrom; and, as noted above, it may be of copper because copper has extremely high heat conducting quality.

As shown in Fig. 3, the float may be oblong instead of circular, and if made of light material, such as aluminum, it may be solid instead of hollow. In this connection, it may be noted that the fusible material can never get much above the boiling point of water, and there are many float materials, lighter than aluminum, that will safely withstand such temperatures.

In the modification shown in Fig. 4, the same or similar parts are identified by the numerals used for Figs. 1 and 2, but with distinguishing exponents. In this Fig. 4, the downtime 1a, throttle valve 2a, operating lever 3a, and water cooled engine 10a, may be the same as in Fig. 1.

The radial arm 8a which rotates with the throttle, may be like that shown in Fig. 1, except that it does not have the curved tip extending beyond the point of engagement with the stop 7b, because its radial length need be only sufficient to ensure safe initial engagement with the upper end of said stop 7b. For this and other reasons, I prefer to make the radial arm 8a, a spring which is very stiff so that the rigid 60 backing arm 9 is not necessary. With this arrangement, the throttle is initially free to swing the spring 8a down to contact with stop 7b, during the warming up period. During this period, the stop 7b is prevented from any vertical movement, by the solid freezing of the float 6a, in the fusible metal 5a, contained in receptacle 4b. It will be noted, however, that the stop 7b, while in vertical alignment with its float-supported 70 shank 7a, is formed with an intermediate curve 7c, whereby all the shank is outside the path traversed by the tip end of the spring 8a; and only the extreme upper stop end 7b, lies in said path.

In order to get full advantage of this curve 75 7c between stop 7b and shank 7a, it is desir-

able to prevent the stop rod from rotating about its vertical axis, out of the position shown in Fig. 4; and this may be accomplished either by making the float 6a oblong, as in Fig. 3, or by giving the stop 7a a rectangular cross section as 5 shown in Fig. 5.

When the motor is hot and the fusible metal liquefied, the float 6a automatically positions itself against the stop projections 4d, 4d, in which position the shank 7a is vertical; so when the 10 throttle is opened and the spring 8a comes in contact with the upper stop end 7b, it encounters practically no resistance because, first, the float is easily depressed, second, the float can tilt to the left thereby causing 7a to swing to 15 the right, by pivoting about the bearing surface at 4e, and, third, the shank 7a is itself slightly flexible and very little camming pressure toward the right will flex it partly or wholly out of the path of the throttle control spring 8a. In other 20 words, the tip 7b operates as an easily-yielding, automatically self-restoring detent that affords no appreciable resistance to any movement of the throttle between tight closed and wide open positions.

During the warming up period, while the motor is cold and the float is frozen in the fusible metal, opening the throttle will cause spring 8a to apply thrust directly downward on stop 7b, and the stiffness of the spring may be selected, 30 so that it can apply any desired resistance to further opening. Preferably the spring will be stiff enough to prevent further opening of the throttle until the fusible metal melts.

In a special case, the flexibilities of the spring 35 8a and shank 7a, may be selected so that in case the operator applies pressure beyond the predetermined limit, the spring 8a will bend upward somewhat as indicated in dotted lines on Fig. 4; and such bowing upward, plus outward flexing of 40 stop shank 7a, may be sufficient to allow the tip of 8a to snap downward past 7b to position where it can straighten out, with its tip in rearward curve 7c, where said tip will be entirely out of contact with 7c and 7a, all the way to 45 wide open throttle. In case of such intentional violent opening of the throttle by the operator, he can race the engine, knowing that he is doing so, but when he releases the throttle, the spring 8a can bend reversely, and again cam shank 7a outwardly, enough so that the tip of 8a can 50 spring past stop 7a, and so automatically return to the initial, closed-throttle, position.

In this Fig. 4 I have shown a light spiral spring 6c submerged in the fusible metal 5a resting on 55 the bottom of the receptacle 4b and applying upward thrust on the float 6a, but this is mainly for the purpose of showing how such a submerged spring may be used as a supplement to or a substitute for the float effect required for restoring the stop to initial operative position, while the fusible metal is liquid, before it freezes. The point is that upward thrust applied by this or any other submerged spring, is like flotation, in that the spring becomes anchored, when the 65 fusible metal freezes, the same as a float does.

There are many other ways of utilizing fusible material as means for anchoring a stop when said material is frozen, yet have the stop easily displaceable when the metal is melted.

Fig. 6 shows a very simple form in which the stop is simply a long, flat spring, that has its lower end seated on the bottom of a very narrow receptacle 4x so that it is vertically unyielding. The spring has its lower two-thirds 7x 75

submerged in the fusible metal 5x in receptacle 4x; and its upper third 7y projects above the receptacle into position for engagement by the spring 8x that controls the throttle. When the 5 fusible metal is frozen, the submerged two-thirds 1x is inflexible and the upper third 7y is relatively stiff, but when the fusible metal melts, the entire spring can easily flex about the bearing edge 4y as a fulcrum, thereby pivoting the upper end 7y out of the path of the end of throttle spring 8x. Thrust to cause such pivoting can only be applied by bending upward the end of 10 throttle spring 8x, so that it will apply an outward camming effect. Hence spring 8x must be 15 flexible enough to bend easily.

It is not necessary to have the opening movement of the throttle limited by a member that is normally in and held by the fusible metal, when it freezes. For instance, in Fig. 7 the down- 20 draft intake 1c, throttle valve 2c, operating lever 3c, correspond with similar parts in Figs. 1 and 4; also the receptacle 4r, fusible metal 4c, fulcrum point 4s and water cooled engine head 10c are in a general way like those shown in 25 Fig. 4. The thrust member 7f corresponds in a general way with the stop 7 in Fig. 1, except in this case it is pivoted to and is carried by the radius arm 8c, instead of being supported by float or by spring.

30 The operation is very simple. In the position shown in full lines, the thrust member 7f has its lower end a predetermined distance above the surface of the fusible metal 5c. When this metal is frozen, the throttle is free to open until the 35 lower end 7g comes in contact with the frozen surface of the metal. Adjustment between these two points is entirely free for variation during the warming up period. When the engine gets hot enough so that the fusible metal melts, the 40 lower end 7g of the thrust member can penetrate the fused metal freely, and to any depth, the thrust member 7f pivoting about the fulcrum edges 4s, to the various positions shown in dotted lines.

45 It will be noted that I have referred to my "temperature-sensitive, resistance-varying element" as having solidification and fusing points such that it remains a solid during warming up temperatures; but melts at warmed up temperatures. In this connection, it will be understood as concerns metal alloys usable for my purpose, that their fusing temperatures and solidification temperatures are not necessarily the same; and, in certain cases, there may be a range of varying 55 mushy or viscous conditions, in which the material is not a "solid" or a "liquid" in the strict sense of those terms. Furthermore, my invention includes other fusible materials which are much less rigid than metals, such as the more 60 solid bitumens; or even materials which are not normally either completely rigid or completely fluid within the range of temperatures at which they normally operate in my apparatus, provided they possess a sufficiently wide range of 65 viscosity within said temperature range.

I claim:

1. A variable-speed, heat-generating mechanism and an adjustable speed-controlling device therefor having a member moving by and in 70 accordance with the adjusting movements thereof, in combination with a body of normally solid fusible material arranged to limit accelerating adjustment of said control member; and also to receive heat from an element having temperature variations corresponding to the internal

temperature variations of said variable-speed mechanism; said fusible material having solidification and fusing points such that it remains a solid, obstructing and limiting accelerating movement of said control member during warming up temperatures of said mechanism; but melts at warmed-up temperatures, thereby permitting movement of said control member throughout its normal range of adjustment. 5

2. Apparatus as specified in claim 1 and in 10 which there is an intermediate thrust member through which the normally solid fusible material obstructs the movement of the movable member of the speed controlling device.

3. Apparatus as specified in claim 1 and in 15 which there is an intermediate thrust member, having one portion always submerged in the fusible material so as to be frozen therein and thereby anchored with an unsubmerged portion 20 thereof in position to serve as a stop to obstruct and limit accelerating movement of the control member.

4. Apparatus as specified in claim 1 and where- 25 in there is an intermediate thrust member sup- ported by a submerged portion which floats in the fusible material when it is melted, and is rigidly supported by said material when it freezes.

5. Apparatus as specified in claim 1 and where- 30 in there is an intermediate thrust member pivot- ed to an arm rotating with the throttle and hav- 35 ing its lower end arranged to be lifted a predetermined distance above the surface of the fusible material, when the throttle is in the closed position, so that when frozen the upper sur- face of said material operates as a solid stop for said thrust member.

6. A variable speed internal combustion en- 40 gine and a throttle valve with adjustable con- trol means for varying the speed of the engine, in combination with a body of normally solid fusible material arranged to limit accelerating 45 adjustment of said control means and also to receive heat from a portion of said engine having temperature variations corresponding to the internal temperatures of said engine; said fusible material having solidification and fusing points such that it remains a solid, obstructing and limiting accelerating movement of said control means during warming up temperatures of said mechanism; but melts at warmed-up tempera- 50 tures, thereby permitting movement of said control means throughout the normal range of adjustment of said throttle valve.

7. A variable-speed internal combustion en- 55 gine and a rotary throttle valve with control means for rotating it to vary the speed of the engine, in combination with a body of normally solid fusible metal arranged to limit accelerating 60 adjustment of said control means and also to receive heat from a portion of said engine hav- 65 ing temperature variations corresponding to the internal temperature of said engine; said fusible metal having solidification and fusing points such that it remains a solid, obstructing and limiting rotary movement of said control means during warming up temperatures of said mechanism; but melts at warmed-up temperatures, thereby 70 permitting rotation of said throttle valve throughout its normal range of adjustment.

8. Apparatus as specified in claim 7 and in 75 which there is an intermediate thrust member through which the normally solid fusible metal obstructs the movement of a movable mem- 75 ber of the adjustable means for controlling the throttle.

9. Apparatus as specified in claim 7 and in which there is an intermediate thrust member, having one portion always submerged in the fusible metal so as to be frozen therein and thereby anchored with an unsubmerged portion thereof in position to serve as a stop to obstruct and limit throttle-opening movement of the adjustable control means.
10. Apparatus as specified in claim 7 and wherein there is an intermediate thrust member supported by a submerged portion which floats in the fusible metal when it is melted, and is rigidly supported by said metal when it freezes.
11. Apparatus as specified in claim 7 and wherein there is an intermediate thrust member supported by a submerged portion which floats in the fusible metal when it is melted, and is rigidly supported by said metal when it freezes; said submerged float portion being substantially 20 aluminum and said fusible metal being an alloy which is of much greater specific gravity than the float.
12. Apparatus as specified in claim 1 and wherein there is an intermediate thrust member pivoted to an arm rotating with the throttle and having its lower end a predetermined distance above the surface of the fusible metal, when the throttle is in the closed position, so that when frozen the upper surface of said fusible metal 30 operates as a solid stop for said thrust member.
13. A heat generating device and an adjustable device for controlling the supply of heat generating medium to said heat generating device, said controlling device having a member moving by 35 and in accordance with the adjusting movements thereof, in combination with a body of normally solid fusible material arranged to limit the initial movements of said controlling device and located in heat receiving relation to an element having temperature variations corresponding to the internal temperatures of said heat generating device; said fusible material having solidification and fusing points such that it remains a solid, obstructing and limiting the initial 40 movement of said control device during warming up temperatures of said heat generating device;
- but melts at warmed-up temperatures thereby permitting movement of said control member throughout its normal range of adjustment.
14. An internal combustion engine and a manually operated throttle adapted to control the speed of the engine, in combination with means thermo-responsive to the temperature of the engine, arranged to impede movement of the throttle so that the throttle cannot be operated to run the engine at high speeds while the engine is warming up to safe working temperature, except by conscious and unusual effort of the operator.
15. An internal combustion engine and a manually operated throttle adapted to control the speed of the engine, in combination with means including a thermo-responsive device in heat receiving relation to an element having temperature variations corresponding to the internal temperatures of said engine, and in position to 20 modify the range of free opening of the throttle; said device having a wide temperature-responsive range such that during warming up of the engine, it affords resistance requiring conscious and unusual effort of the operator to overcome it; 25 but at warmed-up temperatures, decreasing resistance to permit relatively free movement of the throttle throughout its normal range of adjustment.
16. An internal combustion engine and a manually operated throttle adapted to control the speed of the engine, in combination with a body of material having normally high viscosity, located in heat receiving relation to an element having temperature variations corresponding to the internal temperatures of said engine, and in position to limit the range of free opening of the throttle; said material having a wide temperature-viscosity range such that it remains 35 highly viscous; affording substantial resistance to opening of the throttle during warming up temperatures of the engine; but at warmed-up temperatures, having low viscosity to permit relatively free movement of the throttle throughout its normal range of adjustment.

SAMUEL W. RUSHMORE.
